COMBINATION FOLDING ORTHOPEDIC
AND RECLINING BEDBOARD

Frank R. Muenzen, New Rochelle, N. Y.

Application December 28, 1943, Serial No. 515,908

8 Claims. (Cl. 5—71)

The present invention relates generally to bed boards, and it has particular relation to a type of apparatus that is suitable for use in connection with conventional beds such as are found in the average home.

The invention is particularly useful for persons having joint ailments, fractures or other physical disability, which make it highly desirable that there be the minimum flexing of the affected parts while the patient is in bed. It is also useful for persons not so affected, as many people find it impossible to obtain the ultimate benefits from sleeping in a bed which is overly soft or has highly resilient or poor or saggy springs. It is also useful for persons who wish to have the mattress elevated at the head end for reading, eating, or sleeping in an inclined position.

With the present invention, the conventional bed, having either too soft a mattress, or poor, saggy springs, may have this characteristic neutralized and a stiffer or smoother support provided. It also permits the head portion to be raised to a suitable angle or lowered to a level position by one in bed and by a simple and easy operation.

An object of the present invention is to provide a simple, inexpensive and durable foldable bed board made of parts hinged together and adapted to be positioned between the springs and mattress of a conventional bed to convert it into an orthopedic bed with a minimum of effort, time and expense.

Another object of the invention is the provision of a bed board that is made in hinged sections so as to be foldable into a compact unit that may be carried from place to place by one who travels, and quickly, easily and readily applied to a conventional bed with a minimum amount of time and effort.

A further feature of the invention is to provide a bed board that has a reclining or head section that may be raised to an inclined position, and a supporting unit that automatically swings into proper position under said section when the latter is simply raised above the surface of the bed upon which it rests.

Another feature of the invention is the provision of a foldable bed board that may readily be changed from an inclined position to a flat or horizontal position, or vice versa, by the patient or other bed occupant while remaining in the bed, with practically little or no effort.

Other and further objects and advantages of the invention reside in the detailed construc-

tion of the apparatus, which result in simplicity, economy and efficiency, and which will be apparent from the following description, wherein a preferred embodiment of the invention is shown, reference being had to the accompanying drawings, forming a part hereof, wherein like numerals indicate like parts, in which:

Fig. 1 is a side elevational view of a combination orthopedic and reclining bed board embodying the principles of the invention, the same being shown mounted between the springs and mattress of a conventional bed, with a patient lying in a reclining position thereon;

Fig. 2 is a top plan view on a larger scale, of the bed board shown in Fig. 1;

Fig. 3 is a bottom plan view on a similar scale, of the bed board shown in Fig. 2;

Fig. 4 is a longitudinal sectional view of the bed board shown in Fig. 3, the same having been taken along the line 4—4 thereof, looking in the direction of the arrows;

Fig. 5 is another longitudinal sectional view of the bed board shown in Fig. 4, showing the same in its normal elevated position;

Fig. 6 is a longitudinal sectional view of the bed board shown in Fig. 3, the same having been taken along the line 6—6 thereof, and illustrating the same in its normal elevated position;

Fig. 7 is a perspective view of the bed board shown in Fig. 1, illustrating the manner in which it is foldable into a compact unit for shipment or storage; and

Fig. 8 is an edge view of a form in which the main section is flexible rather than stiff.

In the form shown in Figs. 1 to 7, the apparatus includes a horizontal or flat body section 11 and a vertically movable head section 12, having a foldable supporting section 13 mounted on its underside intermediate its ends and provided with a foldable base section 15. Each of the parts may be constructed of any suitable flat sheet-like material such as, for example, metal, plastic, plywood or compressed paper fibre board. In the interest of economy and lightness and splintering, it is preferable to use compressed paper fibre board, which is light in weight, thin, strong and durable, and obviates various disadvantages of the other substances. When the various sections of the board are assembled, they may be covered with the paper 14 having an imitation of grained natural wood, and will last a lifetime under normal wear and care.

The two sections 11 and 12 may have a width approximately the width of a single bed, and the two sections together may have a length approxi-

mately the length of the bed, but preferably a few inches shorter. Each of these sections is rectangular in shape and they are so connected as to permit relative swinging movement. The connecting means may be of any desirable type such, for example, as spaced pairs of woven fabric or tapes 16. Each tape of each pair is fastened adhesively or otherwise to one side of one section and to the opposite side of the other section, as indicated at 17 and 18, and each tape of each pair is mounted oppositely from the other as best shown in Fig. 5.

The section 12, which is referred to as a head section, serves when in raised position, to support not merely the head of the occupant of the bed but also the weight of all or a major portion of the torso, and therefore, this head section may be made of thicker or stronger material, but preferably it is of the same character as the sections 13 and 15 and is provided with a reinforcing panel 24 extending across the width of the underside of the section 12 and along the major portion of the length of the latter.

The supporting unit for the head section 12 includes the supporting section 13 and the base 15, the former having one edge secured to the underside of the section 12 intermediate of its ends. The securing means permits swinging of the section 13 and preferably includes tapes 23 which may extend through spaced slits 22 to form a loop with the free ends thereof criss-crossed so that they extend in opposite directions and project through slits 26 in the panel 24. These ends may be fastened securely in any suitable manner as by adhesive in the space between the underside of the section 12 and the upper side of the panel 24. The vertical member 13 is similarly hinged to the base member 15. As shown, it has slits 27 through which extend tapes 29, the free ends of which are passed through the corresponding slits 28 in the base member 15 and then criss-crossed and securely fixed, either by a suitable adhesive or other desirable means to the underside of the base member.

Any suitable means may be provided for preventing the section 11 from slipping or creeping on its supporting surfaces. This is shown as pads 31 of rubber or other suitable non-sliding material, mounted on the under surface of the section 11, preferably adjacent the end connected to the swingable section 12. Similar means 32 are mounted in spaced relation on the underside of the base member 15.

Means are provided whereby the vertical member 13 is prevented from swinging in one direction past the vertical position. This is shown as a tape 30 secured to the upper end of the section 12 by extending through a slit 33 and to the base 15 by extending through a slit 36 (Fig. 6). To permit the occupant of the bed to easily pull the supporting unit from beneath the section 12 and permit lowering of the latter, there is provided a pull or draw strap 34, one end of which is securely fastened or anchored to the base section. This tape may, if desired, be an extension of the tape 30 or it may merely have one end extended through an aperture 36 in the base 21, and glued in place, or it may be secured by a tack 37, to the underside of the base. The remaining portion of the tape 34 is left free, and is of a length sufficient to extend up and over the head of the reclining member 12 and down over the board sufficiently far to be conveniently within reach of the patient. The free end of the tape 34 may be looped, as indicated at 38, if desired.

While the apparatus may be used in varied ways, with or without a conventional bed, it is primarily designed to be used in connection with a conventional bed. It is, of course, obvious that the size of the board will depend primarily upon the size of the bed with which it is intended to be used. In Fig. 1, the bed board is illustrated in use in conjunction with a conventional bed having a boxed spring 41 and a mattress 42, and it will be noted that the same is intended to be positioned directly between the spring and mattress. Should the patient or user desire to raise the board to a reclining position, it is only necessary to remove his weight from the head section 12 and lift the outer end thereof. As the section 12 is raised, the supporting unit will gravitate into its supporting position, as shown in Figs. 1, 5 and 6, and serve to maintain the section 12 in an elevated inclined position. Should the patient or user become tired of resting in this position and desire to lie flat, he merely has to remove his weight from the section 12 and pull on the loose end of the tape 34, which will draw the base member 15 toward the head of the bed and permit the base 15 to fold against the underside of the section 13, and said section 13 to fold against the underside of the section 12, and the base 15 to fold against the underside of the section 13, as shown in Fig. 4.

The drawings, for purposes of illustration, show the fibre board to be relatively thick, but actually it need be only $\frac{1}{4}$ to $\frac{3}{8}$ of an inch in thickness and about 30 inches wide for an ordinary single bed. Thus, the overlapping layers of the supporting unit under the reclining section does not hold up the head end of the conventional mattress to any noticeable degree.

Although I have described in detail only one embodiment of the invention, it will be apparent to those skilled in the art that the invention is not so limited, but that various modifications may be made therein without departing from the spirit thereof or from the scope of the appended claims. For instance, the horizontal section 11 need not be of stiff material but may be of flexible cloth 11a, glued or riveted to the edge of head section 12, as shown in Fig. 8. In this case, it does not form a stiff support for the mattress, but serves merely as an adequate anchorage for the lower end of the swingable section 12 and prevents the latter from being crowded toward the head end of the bed by pressure thereon when in raised inclined position, as is the case also with the form shown in Figs. 2 to 7. The connection between the sections 11a and 12 will serve as a hinge permitting the raising and lowering of the section 12. Various other types of hinges may be employed, but by making them of tape instead of metal, liability of rusting is avoided. The reinforcing section may be omitted if the section 12 be of the required stiffness and strength. Other connections of the releasing tape 34 may be provided.

Having thus described my invention, what I claim as new and desire to secure by Letters Patent is:

1. As a new article of manufacture, a folding bed board adapted for insertion between the springs and mattress of a bed and comprising a horizontal flat stiff section and a reclining flat stiff section hinged together, said reclining section having a supporting unit mounted on its underside intermediate its ends, said supporting unit consisting of a flat stiff member pivotally connected along its upper edge to the underside of said reclining section and hav-

ing a base member pivotally connected thereto along its lower edge, said supporting unit being adapted to swing automatically into elevating position when said reclining section is raised to its normal sitting position.

2. As a new article of manufacture, a folding bed board adapted for insertion between the springs and mattress of a bed and comprising a main section and a second section hinged together, said second section having a supporting unit hinged thereto on its underside intermediate its ends and including a vertical member connected pivotally along its upper edge to said reclining section and a base member connected pivotally to its lower edge, said supporting unit being adapted to swing automatically into supporting position when said second section is raised, friction means mounted on the underside of the main section for frictionally engaging a supporting surface, and friction means mounted on the underside of said base member for engaging said supporting surface.

3. As a new article of manufacture, a folding bed board comprising two stiff board sections hinged together, one of said sections having a supporting unit mounted on its underside intermediate its ends, said unit consisting of a board member pivotally connected along its upper edge to said last mentioned section and a base member pivotally connected to the lower edge of the other member of said unit, said supporting unit being adapted to swing automatically into elevating position when said reclining section is raised, means mounted on the underside of said horizontal section for frictionally engaging a supporting surface, and means attached to said base for moving the latter over a supporting surface and causing the supporting unit to fold against the underside of the connected one of the first mentioned sections.

4. A folding bed board comprising a main stiff board and a second stiff board hinged together, a stiff board having one edge hinged to the underside of the second board intermediate of the edges of the latter, and a base board hinged intermediate of its edges to the other edge of said third board, whereby upon lifting said second board, said third board is adapted to swing automatically into vertical position and rest on said base board.

5. A folding bed board comprising a main stiff board and a second stiff board hinged together, a stiff board having one edge hinged to the underside of the second board intermediate of the edges of the latter, and a base board hinged intermediate of its edges to the other

edge of said third board, whereby upon lifting said second board, said third board is adapted to swing automatically into vertical position and rest on said base board, and flexible means connected to said base board and having a free end to be grasped manually for moving said base board horizontally and causing it and said third board to fold flat against the underside of said second board.

6. A folding bed board comprising a main stiff board and a second stiff board hinged together, a stiff board having one edge hinged to the underside of the second board intermediate of the edges of the latter, and a base board hinged intermediate of its edges to the other edge of said third board, whereby upon lifting said second board, said third board is adapted to swing automatically into vertical position and rest on said base board, and flexible means for limiting the swinging movement of said third board in one direction past a substantially vertical position.

7. A folding bed board comprising a main soft flexible section and a stiff board hinged together, a stiff board having one edge hinged to the underside of said board intermediate of the edges of the latter, and a base board hinged intermediate of its edges to the other edge of said second board, whereby upon lifting said first board, said second board is adapted to swing automatically into vertical position and rest on said base board, and flexible means for limiting the swinging movement of said second board in one direction past a substantially vertical position.

8. As a new article of manufacture, a folding bed board adapted for insertion between the springs and mattress of a bed and having a main horizontal section and a reclining stiff board section hinged together end to end so as to lie in the same plane with the horizontal section extending toward the foot of the bed, and the reclining section extending toward the head of the bed, the reclining section having a supporting unit comprising a stiff board section of substantially the same width as the first mentioned board sections, and pivotally secured to the underside of the reclining section intermediate of the ends of the latter, said unit being adapted to swing automatically into substantially vertical position when said reclining section is raised, and a flexible member secured to the lower part of said supporting unit and adapted to extend over the upper end of the reclining section for pulling the lower end of said supporting unit away from said main section.

FRANK R. MUENZEN.
